(57) **CLAIM**

I claim, the ornamental design for a frame for a sliding door, as shown and described.

DESCRIPTION

FIG. 1 is a front elevational view of a frame for a sliding door in accordance with my invention;

FIG. 2 is a bottom view thereof, the top view being a mirror image of the bottom view;

FIG. 3 is a sectional view taken along line 3—3 of FIG. 1;

FIG. 4 is a right side elevational view thereof, the left side elevational view being a mirror image thereof;

FIG. 5 is an enlarged left partial perspective view thereof;

and,

FIG. 6 is an enlarged right partial perspective view thereof.
